(57) **CLAIM**

The ornamental design for a storage bag as shown and described.

DESCRIPTION

FIG. 1 is a perspective view of a storage bag showing my new design where the first component is assembled with the second component;

FIG. 2 is an exploded perspective view of the storage bag; FIG. 3 is another exploded perspective view of the storage bag;

FIG. 4 is a perspective view of the first component of the storage bag, shown separately to illustrate aspects of the design that are not visible when combined;

FIG. 5 is another perspective view thereof;

FIG. 6 is a front elevational view thereof;

FIG. 7 is a rear elevational view thereof;

FIG. 8 is a left side elevational view thereof;

FIG. 9 is a right side elevational view thereof;

FIG. 10 is a top plan view thereof;

FIG. 11 is a bottom plan view thereof;

FIG. 12 is a perspective view of the second component of the storage bag, shown separately to illustrate aspects of the design that are not visible when combined;

FIG. 13 is another perspective view thereof;

FIG. 14 is a front elevational view thereof;

FIG. 15 is a rear elevational view thereof;

FIG. 16 is a left side elevational view thereof;

FIG. 17 is a right side elevational view thereof;

FIG. 18 is a top plan view thereof;

FIG. 19 is a bottom plan view thereof;

FIG. 20 is an enlarged view of the portion of the storage bag encircled in FIG. 4; and,

FIG. 21 is an enlarged view of the portion of the storage bag encircled in FIG. 13.

(Continued)

The dash-dash broken lines in the drawings depict portions of the storage bag that form no part of the claimed design. The dot-dash broken lines shown in FIGS. 4, 13, 20, and 21, which form no part of the claimed design, encircle portions of the storage bag that are illustrated in enlargements.
